UNITED STATES PATENT OFFICE.

CHARLES H. RICKERT AND AARON D. ECKERT, OF READING,
PENNSYLVANIA.

DESIGN FOR A BADGE.

SPECIFICATION forming part of Design No. 33,907, dated January 15, 1901.

Application filed June 8, 1900. Serial No. 19,631. Term of patent 7 years.

To all whom it may concern:

Be it known that we, CHARLES H. RICKERT and AARON D. ECKERT, citizens of the United States of America, and residents of Reading, 5 in the county of Berks and State of Pennsylvania, have invented and produced a certain new and original Design for a Badge, of which the following is a specification.

In the drawings, Figure 1 is a plan view of 10 a badge, showing our new design; and Fig. 2 is a sectional view of the same.

As shown in the drawings, the leading or material features of our design consist of the plate *a*, having a central circular medallion 15 *b* in relief thereon, circular grooves *c c* and *d d* concentric with said medallion and form-

ing between them an annular inscription-surface *e*, with separating ornamentation *f* thereon and an annular margin or border *g* beyond the outer grooves *d d*, having parallel ogee 20 ornamental grooves *h* extending obliquely across said border *g*.

What we claim is—

The design for a badge substantially as shown and described.

Signed by us at Reading, Pennsylvania, 25 this 4th day of June, 1900.

CHARLES H. RICKERT.
AARON D. ECKERT.
